DESIGN FOR A BOX

Evelyn Westall, New York, N. Y.

Application May 31, 1946, Serial No. 130,271

Term of patent 14 years

(Cl. D58—11)

To all whom it may concern:

Be it known that I, Evelyn Westall, a citizen of the United States, residing at New York city, in the county of New York and State of New York, have invented a new, original, and ornamental Design for a Box, of which the following is a full, clear and exact description, reference being had to the accompanying drawings, forming a part thereof.

In the drawings:

Figure 1 is a perspective view of a box showing my new design, with the upper part or lid removed from the lower part, or base,

Figure 2 is an elevation of the box shown in Figure 1, with the lid upon the base and thus viewed in closed position, and

I claim:

The ornamental design for a box, substantially as shown.

EVELYN WESTALL.
